SCRUBBING DEVICE

Manuel Carvalho, Somerville, Mass.

Application December 16, 1938, Serial No. 246,221

1 Claim. (Cl. 15—122)

This invention is a device for use in scrubbing, and particularly for use while bathing or scrubbing one's body.

An object of the invention is to combine in a single device of this character, a sponge and soap, the sponge serving to spread the soap suds over the body to insure a thorough cleansing action on the part of the soap, the soap serving to maintain the sponge in a thoroughly "soapy" condition during the use of the device.

The invention together with its objects and advantages will be best understood from a study of the following description taken in connection with the accompanying drawings wherein:

15 Figure 1 is a top plan view of the device.

Figure 2 is a side elevational view thereof with certain parts of the handle removed.

Figure 3 is a plan view of the forked end of the handle.

20 Figure 4 is an end elevational view of the sponge with the handle removed.

Figure 5 is a sectional view taken substantially on the line 5—5 of Figure 6.

Figure 6 is a sectional view taken substantially 25 on the line 6—6 of Figure 4.

Figure 7 is a top plan view of the sponge showing the slit provided for the insertion of a bar of soap into the well or pocket provided therefor in the sponge, and

30 Figure 8 is a transverse sectional view through the forked end of the handle showing the use of a spring latch therewith.

Referring more in detail to the drawings it will be seen that in accordance with the present invention there is provided a sponge 5 that is of block-like form and is provided with a soap chamber or well 6 that opens at the top side of the sponge 5. Sponge 5 also is provided with an opening 7 leading from the bottom of the well 6 to the opposite side of the sponge and through which the soap suds may escape to cover the surface of the sponge.

The top side of the sponge body has cemented or otherwise secured thereto a sheet 8 of rubber 45 which at its center is provided with a slit 9 which may be expanded laterally for the insertion of the bar 10 of soap into the well 6 of the sponge 5.

Cemented, vulcanized, or otherwise secured to the backing sheet 8 are narrow pieces 11 of relatively hard rubber so arranged as to abut at one longitudinal edge thereof when the sponge is in its contracted or normal condition.

At the outer longitudinal edges thereof the pieces 11 are provided with integral longitudi-

nally extending hooks 12 which are elongated longitudinally of the rubber pieces 11.

For the device there is also provided a handle which embodies a shank 13 of wire, said shank 13 at one end being equipped with a hand-grip 14 of wood or other suitable material and an eye 15 through the medium of which latter the device may be suspended from a nail or other suitable suspension element.

At the opposite end thereof the shank 13 is provided with an integral fork 16.

The fork 16 is formed by bending the wire from which the shank is formed into a substantial U, the legs 17 of which are provided with reverse bends 18 which at the closed end of the 16 U are directed towards one another and then relatively twisted for the remaining length of the wire to provide the shank 13.

Thus double-ply legs 17 for the fork are provided and at the closed end of the U the bight 20 of the fork is also bent into a substantial U 19 that extends inwardly between the legs 17 and serves, as will be hereinafter made manifest, as a tension device.

For bridging the free ends of the legs 17 at the 25 open end of the U, and for urging said legs 17 inwardly toward one another there is provided a latch bar 20 formed of spring metal. At one end thereof the latch bar 20 is formed into an eye 21 that is engaged with the reverse bend 18 30 of one of the legs 17. At the opposite end thereof the latch bar 20 is formed into a hook 22 that is adapted to spring into engagement with the reverse bend 18 of the other leg 17 as shown in Figure 8 for securing the legs 17 under tension 35 and thereby maintain the legs in engagement with the hooks 12 of the handle-fastener plates 11.

To use the device the sponge 5 is separated from the handle and distorted in an obvious manner to enlarge the slit 9 to permit the bar 10 of soap to be placed in the well 6 after which the sponge 5 is permitted to return to its normal shape.

The legs 17 of the handle are then engaged, 45 in an obvious manner with the hooks 12 of the plates 11 and the latch 20 then placed in bridging relation to the legs 17 and engaged therewith to urge the legs inwardly towards one another to thereby retain the legs 17 engaged with the 50 hooks 12; the projection 19 being accommodated between the hooks 12 and having a tendency to spread these hooks apart in opposition to the latch 20 and the inherent tendency of the legs 17 to spread apart. Thus projection 19 and latch 55

20 cooperate for positively securing the fork 16 of the handle engaged with the soap-filled sponge 5.

Obviously the sponge is wetted in the usual 5 manner resulting in the formation of suds with which the sponge will become impregnated. With the sponge so "soaped," the device may be used in an obvious manner for thoroughly scrubbing the body, while bathing, or the device, if desired, 10 may also be used for scouring pots, pans, dishes, and the like; it being obvious that the device may be used with facility either as a bathroom or a kitchen accessory.

It is thought that a clear understanding of the 15 construction, utility and advantages of an invention of this character will be had without a more detailed description.

Having thus described the invention what is claimed as new is:

In a scrubbing device of the character described, a sponge of block-like form having a well therein opening at one side of the block, a back-
ing sheet of elastic material secured to the said side of said block and covering the well, said sheet being provided with a slit through which access is had to said well, strips of elastic material connected with the outer face of the sheet, 10 one on one side of the slit and the other on the opposite side thereof with the adjacent edges of said strips being adjacent the walls of said slits and hooks formed on the outer edges of said strips and adapted to be engaged by a handle member. 15

MANUEL CARVALHO.
